UNITED STATES PATENT OFFICE.

FLORENZ M. EGAN, OF NEW YORK, N. Y.

LIGHTING-FIXTURE.

1,078,339.

Specification of Letters Patent. Patented Nov. 11, 1913.

Application filed May 22, 1913. Serial No. 769,342.

To all whom it may concern:

Be it known that I, FLORENZ M. EGAN, a citizen of the United States, residing at New York city, in the county of New York and State of New York, have invented certain new and useful Improvements in Lighting-Fixtures, of which the following is a specification.

This invention relates to lighting fixtures of the hanging type and particularly adapted for use with an electric lamp.

The object of the invention is to provide improved means for holding the lamp globe or shade such as a hemisphere, which in closes or extends under the lamp for diffusing the light thereof. The shade is supported by means of a ring which is hinged to another or inner ring which is suspended from above, so that the former can be flung down for the purpose of cleaning the shade or changing the lamp.

A further feature of the invention is the use of a cover or top plate which may be of clear glass and which is supported by the inner rim, and keeps dust out of the bowl or hemisphere.

A further feature of the invention is that the supporting arms for connecting the ring to the hanger are concealed within the shade, which is advantageous for decorative purposes.

In the accompanying drawings, wherein one embodiment of the invention is illustrated—Figure 1 is a central vertical section of the fixture. Fig. 2 is a top view.

The fixture is hung from above in any suitable manner, such as by a chain 6 and a ring 7 connected to a block 8 into which a stem 9 on the ring 7 is screwed. The block 8 fits within the top of the metal bell or shell 10 and is clamped by the screw stem 9 extending through the top of the bell. The socket 11 of the lamp 12 is attached to the block 8, the lead wires 13 coming in through the stem 9. A plurality of arms 14 connect the block 8 and the inner ring frame 15, the outer part of the arms extending substantially horizontally and the inner part extending vertically to be inserted within the bell 10, which also incloses the lamp socket. These arms are therefore not visible, at least when the fixture is seen from below.

An outer or lower holder ring 16, angular in cross section, is hinged at 17 to the inner ring 15, and this outer ring supports the bowl or hemisphere 18; which will preferably be made of opal or translucent glass having diffusive qualities. At the side opposite the hinge the rings are detachably fastened together by a screw 19. The fixture may be provided with a cover or upper glass 20, which may be made of clear glass to give indirect lighting, and this glass has a central hole into which the lower end of the bell 10 fits. The outer edge of this glass may rest in a rabbet 21 whereby it is held in position, or it may rest on the arms 14. It will be seldom necessary to remove it after the fixture is assembled, but it may be slipped off by disconnecting the chain and lead wires, and when in place it serves to close the top of the hemisphere and keep out dust. The rim 22 of the hemisphere rests on the lower flange of the ring 16, and is held between the same and the ring 15.

To change or clean the shade 18, or to change the lamp 12 the screw pin 19 is removed and the shade and lower ring swung down on the hinge 17 to open the fixture. The only exposed parts are the shade, the outer ring, the metal bell, (which may be made ornamental), and the hanging connections. The weight of the shade is supported by the rings 16 and the arms 14, and the latter are concealed within the bell and under the cover 20. A very simple and decorative fixture is thus produced which can be easily and quickly opened to change the lamp or clean the shade whenever necessary.

What is claimed as new is:

1. A lighting fixture comprising a hanging device, a bell thereon, arms extending within said bell to connection with said device, a lamp socket connected to said device within the bell, and a shade holder supported by said arms, and extending around the bell and adapted to hold a shade under the arms and the lamp, said shade holder being movable from the arms, with the shade, to permit access to the lamp socket and the interior of the shade.

2. A lighting fixture comprising a suspended block, arms projecting therefrom, a bell inclosing the block and the inner ends

of the arms, a lamp socket attached to the block, within the bell, a ring attached to the outer ends of the arms, a shade holding ring hinged to said ring, and a glass cover located over the arms and resting on said first mentioned ring and having a central opening in which the lower end of the bell fits.

In testimony whereof, I affix my signature in presence of two witnesses.

FLORENZ M. EGAN.
